UNITED STATES PATENT OFFICE.

EDWARD TINKHAM GIBSON, OF BROOKLYN, NEW YORK.

COPY-HOLDER.

1,284,889.

Specification of Letters Patent. Patented Nov. 12, 1918.

Application filed August 10, 1918. Serial No. 249,301.

To all whom it may concern:

Be it known that I, EDWARD TINKHAM GIBSON, a citizen of the United States, and a resident of the city of New York, borough 5 of Brooklyn, in the county of Kings and State of New York, have invented a new and Improved Copy-Holder, of which the following is a full, clear, and exact description.

10 This invention relates to holders for copy-bearing stationery and has for an object the provision of a copy holder adapted to hold loose-leaf copy or an end-bound note book in a downwardly and forwardly inclined 15 position.

Another object in view is the provision of a copy holder which is formed with a movable line guide which is adapted to align with any width of the copy.

20 These objects are accomplished by the device illustrated in the accompanying drawings in which Figure 1 is a perspective view of a copy holder disclosing an embodiment of my invention.

25 Fig. 2 is a plan view on a reduced scale of the line guide and its holder, the full lines showing the normal position of the holder arms and the dotted lines the sprung position which the arms will assume if the 30 line guide is removed.

Fig. 3 is a fragmentary cross-sectional view through Fig. 1 on line X—X.

Referring to the accompanying drawing by numerals, 1 indicates a support having 35 a base 2 and an upright 3. Attached to the upper end of the upright 3 is a shelf 4 which is inclined downwardly and forwardly and rests on the forward end 5 of the base 2 and projects below the base 2 to accomplish 40 the first mentioned object of my invention.

45 6 indicates a stop-strip having its longitudinal axis in parallel relation with the transverse diameter of the said shelf 4 and is secured to the latter near the lower end 45 of the same to project forwardly to prevent the downward sliding of a sheet of stationery, 7, from off the front surface of the shelf.

50 A pair of looped members 8 and 9 are secured to the shelf 4 near the lower end and act as hangers for the bar 10, which bar merges into resilient side arms 11 and 12, said arms having, preferably, turned ends,

13 and 14. A line guide 15 is provided, said line guide having apertured ends 16 and 17 55 slidably fitted on the arms 11 and 12 whereby the guide may be moved to any line on copy-bearing stationery suitably disposed on the said shelf 4. As shown in Fig. 2 the arms 11 and 12 are resilient whereby the 60 spreading strain on the line guide 15 will cause said guide to remain in any position in which it is placed.

For holding a stenographer's end-bound note-book, 18, a fragment of which is shown 65 in Fig. 1, on the shelf 4 a book-hanging member 19 is provided, said book-hanging member comprising a central bar portion 20 positioned in front of the front surface of the shelf 4 and having its longitudinal axis 70 in parallel relation with the transverse axis of the said shelf, the said bar portion 20 merging into rearwardly bent portions 21 and 22 that are loosely fitted in slots 23 and 24, respectively, formed in the shelf 4. The 75 said portions 21 and 22 merge (as shown in Fig. 3) into bent ends 25 and 26 respectively, and these ends 25 and 26 are positioned at a suitable distance from the said bar portion 20 to adapt the latter to be 80 drawn forwardly away from the front surface of the shelf 4 a suitable distance to admit of the back portion 27 of a stenographer's end-bound note book 18 being slid 85 downwardly between the shelf 4 and the said bar 20 to hang the said book on the said bar 20.

In Fig. 1, 28 indicates turned-back leaves of the stenographer's note book 18, and it 90 will be seen that the turned ends 13 and 14 of the arms 11 and 12, respectively, are adapted to hold the said leaves 28 in a turned-back condition.

What I claim is:

1. A copy holder comprising a shelf for 95 holding copy, a book-hanging member on the said shelf for hanging an end-bound note book on the face of said shelf, a pair of looped members arranged on said shelf, a pair of resilient arms journaled in said 100 looped members, and a line guide slidably mounted on said arms; said arms having turned ends for holding turned-back leaves of the said note book away from the face 105 of the remaining portion of the note book.

2. A copy holder comprising a shelf for

holding copy, a book-hanging member on the said shelf for hanging an end-bound note book on the face of said shelf, a loop member arranged on said shelf, an arm journaled in said looped member, said arm having a turned end for holding turned-back leaves of the said note book away from

the face of the remaining portion of the note book.

EDWARD TINKHAM GIBSON.

Witnesses:

GEORGE R. HOBBY, Jr.,

CHARLES CRAWFORD.
